LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,126,944.

Specification of Letters Patent.

Patented Feb. 2, 1915.

Application filed June 9, 1914. Serial No. 842,927.

To all whom it may concern:

Be it known that I, LEWIS C. BAYLES, a citizen of the United States, residing at Easton, in the county of Northampton and State 5 of Pennsylvania, have invented a certain new and useful Improvement in Fluid-Operated Percussive Tools, of which the following is a specification.

This invention relates to fluid operated 10 percussive tools, and more particularly to tools of the type wherein the admission of fluid is controlled primarily by the movement of the piston.

The object of this invention is to provide 15 auxiliary valve mechanism for controlling the intake to one end of the cylinder and the exhaust of fluid so that the efficiency of the tool is increased.

With this object in view, a tool has been 20 devised, a practical embodiment of which is shown on the accompanying drawings, in which,

Figures 1 and 2 show diagrammatical longitudinal sections through the tool with the 25 piston and valve in different positions.

In the drawings is shown a tool having a cylinder 1 comprising a smaller rearward bore 2 and a larger forward bore 3. Sliding in the cylinder is a piston 4 having a head 5 30 sliding in the forward bore and a shank 6 sliding in the rearward bore, there being a neck 7 between the head 5 and shank 6. The piston has, therefore, two smaller pressure surfaces for driving it forward and a larger 35 surface for driving it rearward.

Fluid is admitted constantly to the rear 40 end of bore 2 by a passage 8. From the passage 8 a passage 9 extends along the bore 2 opening into the bore 2 near its forward end at such a point that at the end of the rearward stroke of the piston, fluid pressure is admitted to the rear end of bore 3, there being thus an intermittent pressure on the rear face of the head 5. Along the side of bore 45 2 is a valve chest 10. Into the side of this chest 10 near its rear end a front end supply port 11 opens. From the side of the valve chest 10 a little forward of the port 11 a passage 12 leads to the extreme front end of the cylinder. Forward of this an exhaust 50 port 13 leads to atmosphere, while still further

ther forward is the opening of an exhaust passage 14 which leads from the side of the bore 3 at such a point that it will be uncovered by the rear face of piston head 5 soon 55 after passage 9 is closed by the shank 6 of the piston. Sliding in the valve chest is a valve 15 which has a shank and two heads, these being so arranged that in the rearward position of the valve passage 12 will be connected with exhaust port 13, while in the forward position of the valve, passage 12 will be connected with front end supply port 11 while exhaust passage 14 will be connected with port 13. To supply pressure to 60 move the valve a passage 16 leads to the forward end of the valve chest from the rear end of bore 3, while a passage 17 leads from bore 2 to the rear end of the valve chest from a point farther forward than port 11, 65 the passage 17 also serving to supply fluid during part of the stroke to the passage 12 when the valve is in its forward position. From the rear end of the valve chest, a leak port 18 leads to atmosphere. To aid the 70 movement of the valve an auxiliary exhaust port 19 is provided in the side of the bore 3, this port being so placed as to be uncovered by the piston head near the end of its stroke in either direction. 75

In operation, supposing the parts to be in the positions shown in Fig. 2, fluid is being admitted to the rear ends of bores 2 and 3, while the front end of bore 3 is open to exhaust through passage 12 and port 13 and 80 also through auxiliary exhaust port 19. As there is no pressure in the rear end of the valve chest by reason of the leak port 18, and there is live pressure in the front end of the valve chest, the valve will be thrown rearwardly closing port 11. The pressure on the rear surfaces will drive the piston forwardly the fluid in the rear end of bore 3 acting expansively after admission is cut off through passage 9. As the piston moves 85 forwardly the rear face of the piston head uncovers passage 14 but the valve 15 prevents escape of fluid. When the piston reaches the forward end of its stroke, the rear face of the piston head will uncover 90 auxiliary exhaust port 19 exhausting the fluid in the back end of the bore 3 and hence 95 100

in the forward end of the valve chest 10. At the same time the rear face of the shank 6 will uncover passage 17 allowing fluid under pressure to enter the rear end of the valve chest 10 and throw the valve 15 forward. This will allow fluid to pass to the forward end of the bore 3 through the passage 12, while at the same time passage 14 will be connected with port 13. This position of the 10 parts is shown in Fig. 1. The piston will therefore move rearwardly the admission of fluid to the front end of bore 3 continuing until the rear end of the shank 6 cuts off port 11. When the piston nears the rear end of 15 its stroke pressure will again be admitted to the back end of bore 3 and hence the forward end of the valve chest 10, while the fluid in the rear end of the valve chest will be exhausted through passage 12 and port 19 20 and also through leak port 18, the valve moving rearwardly and the above cycle of operations being repeated.

Although the tool as here shown has intermittent pressure in the rear end of bore 3, 25 this might be eliminated and the valve 15 only control the admission and exhaust to the front end of bore 3, and it is to be understood, that while the present showing and description discloses only one specified 30 modification of this invention, other forms and modifications are included in the spirit and scope of the invention as expressed in the claims.

What I claim is:—

- 35 1. In a fluid operated percussive tool, a cylinder of two diameters, a piston therein having a head and a shank, means for exerting a constant pressure on the end of said shank, a passage leading to the other end 40 of the cylinder, a supply port opening from said constant pressure portion of the cylinder, an exhaust port, a valve adapted in one position to connect said supply port and said passage and in the other position to 45 connect said exhaust port and said passage, an operating surface on said valve, and a passage leading from a point in said constant pressure cylinder portion inward of said supply port to convey fluid to said operating surface; said second passage also 50 serving to supply fluid to said first passage.
2. In a fluid operated percussive tool, a cylinder of two diameters, a piston therein having a head and a shank, means for exerting a constant pressure on the end of said shank, a passage leading to the other end 55 of the cylinder, a supply port opening from said constant pressure portion of the cylinder, an exhaust port, a valve adapted in one position to connect said supply port and 60 said passage and, in the other position to connect said exhaust port and said passage, an operating surface on said valve, and a passage leading from a point in said con-

stant pressure cylinder portion inward of 65 said supply port to convey fluid to said operating surface.

3. In a fluid operated percussive tool, a cylinder of two diameters, a piston therein having two small surfaces for driving it 70 in one direction and a surface for driving it in the other direction, means for exerting a constant pressure on one of said smaller surfaces, a passage leading from the constant pressure portion of the cylinder for 75 conveying pressure to exert an intermittent pressure on said larger surface, a passage controlled by the piston for conveying fluid to exert an intermittent pressure on the 80 other of said smaller surfaces, exhaust passages for said intermittently supplied surfaces and valve mechanism for controlling said larger surface supplying passage and said exhaust passages.

4. In a fluid operated percussive tool, a cylinder of two diameters, a piston therein having a head and a shank, means to admit fluid to a portion of the cylinder for exerting a constant pressure on the end of the shank, a passage controlled by the piston 90 for admitting fluid from said constant pressure cylinder portion to exert an intermittent pressure on the inner face of said piston head, a passage for admitting fluid from 95 said constant pressure portion of the cylinder to exert an intermittent pressure on the outer surface of said piston head, exhaust passages for said intermittently supplied cylinder portions, a valve to control 100 said piston head outer surface supplying passage and said exhaust passages and means for moving said valve to open said supply passage and close the exhaust passage for said piston head outer surface near the end of the piston stroke in one direction, and to close said supply passage, open said 105 exhaust passage for the piston head outer surface and close said exhaust passage for the piston head inner surface near the end of the piston stroke in the other direction. 110

5. In a fluid operated percussive tool, a cylinder, comprising a smaller rearward bore and a larger forward bore, a piston in said cylinder, having a head and a shank, means for admitting fluid constantly to the 115 rear end of said small bore, a passage from said small bore controlled by said piston for conveying fluid intermittently to the rear end of said large bore, a valve chest, a front end supply port leading from said small bore to said valve chest, a fluid passage leading from the valve chest to the front end of the large bore, an exhaust passage leading from the rearward part of the large bore to said valve chest, an exhaust 120 port from said valve chest, a valve in said chest so arranged as to connect in one position said front end supply port and said 125

front end fluid passage, and said large bore rear end exhaust passage and said exhaust port, and in the other position to connect said front end fluid passage and said exhaust port, and means for operating said valve.

In testimony whereof, I have hereunto set my hand.

LEWIS C. BAYLES.
